ENGINE ANALYZER WITH SELF-SYNCHRONIZING SWEEP John E. Lindberg, Jr., 3296 Springhill Road,
Lafayette, Calif.Filed June 23, 1955, Ser. No. 517,577
18 Claims. (Cl. 73—116)

This invention relates to an improved engine analyzer and more particularly relates to a positively synchronized sweep circuit for an engine analyzer.

Engine analyzers, such as the one illustrated in my earlier Patent 2,518,427, are used to investigate the performance of engines while they are in actual operation. Certain signals from any of various parts of the engine are impressed across one set of deflection plates in a cathode ray oscilloscope, and a sweep circuit is impressed across the other set of deflection plates. The result is a pattern that, when studied, indicates the performance of the engine.

Synchronization of the sweep circuit with the engine signal circuit has been a very difficult problem. Heretofore, sweep circuits have been initiated independently of the engine by charging and discharging a condenser or by some other means that varies the voltage at a uniform rate over a predetermined period of time, so as to change the voltage differential between the cathode ray plates uniformly with time. But this type of sweep circuit was unable to cope with the synchronization problem, because an engine necessarily operates at different speeds, which vary tremendously. Whenever the engine speed changed, the sweep circuit tended to lengthen or shorten the diagram, and measurement of absolute lengths along the diagram became meaningless, since the lengths could not be related directly to engine conditions.

The prior art sought to solve this problem by providing, in various ways, compensation from an engine-initiated pulse. A typical compensator is shown in the E. F. Weller, Jr., et al., Patent No. 2,645,715. There, the charging rate of the sweep-generating condenser is regulated by a circuit which is controlled by pulses from the engine, to provide a constant amplitude sweep circuit. In other words, the independent sweep circuit was modified in the attempt to synchronize the voltage change with the engine speed. The modifying circuit for this compensating apparatus was very complex; the one referred to in E. F. Weller, Jr., et al., Patent 2,645,715 utilized six electronic tubes plus a mechanical circuit breaker. The best circuit currently in use is even more complex, and includes eleven electronic tubes. This reliance on compensators has left synchronization a difficult and expensive problem; special items of equipment, such as special generators, have been required; and the results have still not been completely satisfactory, especially during periods of acceleration and deceleration of the engine being studied.

I have solved these problems by a new approach to the sweep circuit. My invention obtains its sweep circuit synchronization directly from the engine being analyzed. My new sweep is always necessarily in phase with the engine signal, and synchronization of the sweep with the engine cycle is completely unaffected by changes in speed.

In addition to achieving the object of perfect synchronization, my sweep circuit has other remarkable features; it uses a standard generator which may already be on the engine, and contains no other moving parts. It makes it possible to time the initiation of the sweep directly in the cabin of the plane instead of having to make adjustments in the engine. In addition, as will appear, the engine provides a sweep circuit of great versatility; the type of sweep can be varied for different kinds of analysis simply by throwing a switch which changes circuit impedance.

2

In brief, my invention contemplates obtaining the basic sweep signal from a generator driven by the engine and running at engine cycle speed. In a typical example, two currents ninety degrees out of phase are obtained from the single generator, and these are impressed upon the two pairs of deflection plates of an auxiliary cathode ray tube so as to give a circular sweep. This signal—an electron beam moving in a circle—is used as a light source, and the light is passed through an optical wedge to a light-sensitive transducer. The resulting electric signal, properly amplified if necessary can then be impressed across the sweep plates of the cathode ray tube of the engine analyzer itself. Basically, then, the invention operates by first using an engine to generate a circular sweep of light whose cycle therefore depends directly on the engine cycle; this circular-moving light beam is then used in combination with an optical wedge and a photo-transducer to produce a varying electric voltage suitable for control of the engine analyzer sweep circuit.

20 Other features, objects, and advantages of the invention will become apparent from the following description presented in accordance with 35 U.S.C. 112.

In the drawings:

FIG. 1 is a diagrammatic representation of an apparatus and simple circuit embodying the principles of my invention.

FIG. 2 is a view in front elevation of one form of optical wedge suitable for use in my invention, wherein the light transmission varies uniformly with angular position around a full 360° cycle.

FIG. 3 is a view similar to FIG. 2 of another type of optical wedge also useful with my invention, wherein the light transmission varies uniformly with angular position over a small angle and remains unchanged over the remainder of the cycle.

FIG. 4 is a view similar to FIG. 2 showing another type of optical wedge I employ, wherein a square wave can be generated by having two arcs of different transmission, each arc maintaining its own transmission at a uniform level.

FIG. 5 is a view similar to FIG. 2 of another type of optical wedge wherein there is a series of arcuate segments made up of two types, which alternate. In one type each segment extends the same arcuate distance and varies uniformly in transmission with its angular position. Each of the other arcuate segments extends an identical arcuate distance and maintains a uniform light intensity at the level of the end of the preceding variable segment.

FIG. 6 is a view similar to FIG. 2 of another type of optical wedge, wherein there are two segments, one of which is relatively short and varies uniformly over its arc between zero transmission and fifty percent transmission, while the other, much longer, segment varies uniformly over its arc from fifty percent transmission and one-hundred percent transmission.

FIG. 7 is a diagram, plotting angle of light wedge against percent of light transmission, for each of the wedges shown in FIGS. 2 to 6, and corresponding to the final sweep curve for each wedge.

FIG. 8 is an illustration of one type of engine analyzer pattern, obtained from a signal initiated by the engine and from the sweep given by the wedge of FIG. 2.

FIG. 9 is an illustration of a pattern obtained from the same engine signal as that of FIG. 8 but using the sweep given by the wedge of FIG. 3.

FIG. 10 is an illustration of a pattern obtained from the same engine signal as FIGS. 8 and 9, using the wedge of FIG. 6 to obtain the sweep.

FIG. 11 is an illustration of another type of pattern, obtained from a different engine signal, using the sweep given by the wedge of FIG. 2.

FIG. 12 is an illustration of a pattern obtained from the

same signal as that of FIG. 11 but using the sweep given by the wedge of FIG. 5.

FIG. 13 is a view similar to FIGS. 2 to 7, showing a four-band combination wedge, having annular bands at different radii to correspond to the wedges shown in FIGS. 2, 3, 4, and 6.

FIG. 14 is a view similar to FIG. 2 showing a wedge that is indexed as to angular position.

FIG. 15 is a view similar to FIG. 14 showing a disc that is adapted to overlie any of various wedges and index its angular positions.

FIG. 16 is a diagrammatic view showing a more complex apparatus and circuit than FIG. 1, but also embodying the principles of my invention.

FIG. 17 is a view showing a modified form of circuit for obtaining the circular sweep directly from a three-phase generator.

FIG. 18 is a view showing another modified form of circuit, for obtaining the circular sweep indirectly from a three-phase generator.

FIG. 19 is a view showing another modified form of circuit, for obtaining the circular sweep directly from a single-phase generator.

FIG. 20 is a view showing another modified form of circuit for obtaining a circular sweep from a three-phase generator.

FIG. 21 is a view showing another modified apparatus and circuit omitting the lens.

FIG. 22 is a diagram similar to FIG. 7, on a reduced scale, showing the curve produced by a calibrated wedge of FIG. 14.

FIG. 23 is an illustration of a pattern like that of FIG. 1, but using the calibrated wedge of FIG. 14.

FIGS. 24 and 25 are diagrams of other modified forms of circuit, employing also novel wedge means and cycle switches.

FIG. 26 is a fragmentary view of a modified form of multiwedge discs.

FIG. 27 is a diagram of a modification of a portion of the FIG. 16 circuit.

1. SIMPLE ANALYZER USING THE PRESENT INVENTION (FIGS. 1 AND 21)

While some of the applications of my invention involve complex circuits and apparatus, many of the basic principles are illustrated in the simple analyzers shown in FIGS. 1 and 21, and the more complex applications will be better understood after considering this simple and practical embodiment.

(a) A Simple Circular Sweep

There are many ways of obtaining a circular sweep, several of which are shown in the drawings, but two of the simplest are shown in FIGS. 1 and 21. In each, an engine 20 to be analyzed drives a rotatable magnet 21 in a two-phase generator 22 at engine cycle speed, which, in an airplane engine, is one-half the crankshaft speed. The two-phase generator 22 has two stationary coils 23 and 24 located ninety degrees out of phase. Lead wires 25 and 26 extend from the coil 23 to a cathode-ray tube 30 and place a varying (sine wave) potential across the horizontal deflection plates 31, 32. Similarly, lead wires 27, 28 from the coil 24 place a varying (sine wave) potential, 90° out of phase with the prior signal, across the vertical deflection plates 33, 34 of the tube 30. This affects an electron beam 35 causing it to move in a circular path 36 on a fluorescent screen 37 (of the instantaneous type with as little persistence lag as possible), once per engine cycle. This method of obtaining a circular sweep is well-known in the art. For many uses, the sweep need not be perfectly circular; distortion and irregularities that do not affect synchronization of the angle of the closed sweep with the engine cycle can, for many purposes, be disregarded.

(b) The Optical Wedge 40

The next step is the transmission of the light signal 36 from the cathode-ray tube 30 through an optical wedge 40, preferably in contact with the cathode-ray tube, but shown apart therefrom for illustrative purposes only. The wedge 40 shown in FIG. 1 is a sheet 41 of film, glass or other transparent material on which is impressed (as by photographic or other printing or by a controlled metallic deposit in vacuum or by any other suitable means) a pattern 42, in which the light transmission increases at a constant rate from zero (or very low) transmission at 43 (0°) to full (or very high) transmission at 44, which is just short of 360°. In other words, the electron beam 35 moving in a circle is utilized to produce a beam of light 36, due to the action of the beam 35 on the fluorescent screen 37. The light beam 36 moves in a circle; therefore, when the light beam 36 is at 0° there will be no transmission through the wedge 40, and the transmission will increase uniformly as the light moves in its circular path until it reaches its full value at 359° plus and then at 0° the new cycle begins again at full intensity.

Obviously, different types of optical wedges can be used, some of which will subsequently be described. But the wedge 40 will produce a rotating beam 45 whose intensity varies uniformly with its angular position as it moves around a circle, the light intensity increasing at a uniform rate from nothing to its full amount and then sharply falling to nothing as the next cycle begins. Moreover, the cycle is obviously in perfect phase with the engine 20.

(c) The Lens 48 (FIG. 1 Only)

The next step in the FIG. 1 device is to focus the rotating beam 45 of changing intensity on a single motionless spot 47, so that instead of appearing as a beam 36 moving in a circular path, it will appear as a single stationary beam with varying intensity. This is accomplished by a lens 48 placed at the proper distance from the wedge 40 and focused on the spot 47.

This step is omitted in the FIG. 21 device.

(d) The Light-Sensitive Transducer 50

The varying intensity of the light spot 47 (in FIG. 1) is now used to obtain a correspondingly varying electrical signal, by locating at this focusing stationary spot 47 a photo-transducer 50, which may be a photo-electric cell or any other light-sensitive means of producing or changing a voltage. The photo-transducer 50 senses only a change of intensity in light and produces directly proportional changes in voltage in a lead 51. (If the change in the transducer is not linear, it can be compensated for in the wedge.) This voltage may be amplified by any suitable means such as an amplifier 52, to obtain a voltage of the desired amplitude in the lead 53.

While the lens 48 is useful and convenient, it is not necessary, as shown in FIG. 21. Here all the elements are the same as in FIG. 1, and are given the same numbers, except for the photo-sensitive cell 50a, which is, in this instance, a large one relative to the cathode ray tube 30, uniformly sensitive at all points on its surface. Operation is therefore identical to that described in connection with FIG. 1. The intensity of the light beam 37 is varied in exactly the same way by the wedge 40, to give the beam 45 of varying intensity, and the resultant sweep circuit is identical to the one shown in FIG. 1. Since the tube 30 can be a one-inch tube, there are photo-sensitive tubes 50a on the market capable of reacting properly and uniformly to the beam from such a tube without a lens. With large tubes 30, the lens 48 can be used less expensively than making a large tube 50a.

The photo-transducer 50 or 50a must be of a type that has a high response rate. This is mentioned because some photo-transducers are slow to respond; they lag behind energy changes and do not recover quickly at the point

where a new cycle begins. The response rate must necessarily be high enough to reflect within small tolerances the change in light intensity which the wedge 40 produces in the light beam. Preferably it should respond in a few microseconds, and this can be obtained from available vacuum phototubes, gas phototubes, and photomultipliers. Photomultipliers have the advantage that they make it possible to eliminate any additional amplifier 52, if that is desirable, and can be connected directly to the analyzer tube 55.

Since the device is an optical system from the auxiliary cathode ray tube 30 to the photo-transducer 50, the system is best protected from stray light by enclosing it in a shield 54, which may have light-reflecting walls beyond the wedge 40.

The amplifier 52, if needed and used, is preferably of the push-pull type and can be provided with a variable control for determining the length of the ultimate sweep, so that the complete engine cycle can take up the full width of the tube 55, or only a part of the engine cycle (e.g. the ignition of one cylinder) can take up the full width of the tube.

(e) *The Engine Analyzer Cathode Ray Tube 55*

The varying signal from the photo-transducer 50 having been amplified is now ready to be impressed across the sweep plates of the engine analyzer cathode ray tube 55. As shown, this may be accomplished by grounding one of the plates 56, while the lead wire 53 from the amplifier 52 is connected to the opposite plate 57. This means that the electron beam 58 in the tube 55 will move across the tube 55 from the plate 57 to the plate 56 (or the reverse) during each engine cycle and will, at the end of each cycle, snap back to the plate 57 and begin moving again during a new cycle. The rate of speed of the beam 58 is constant if the engine speed is constant; if the engine speed changes, the speed of movement of the beam 58 changes. Therefore, the position of the beam 58 relative to the engine cycle is constant, with any given wedge. If the engine slows down, the beam slows down, until the engine stops and the generator 22 ceases to produce the sweep. If the engine 20 runs faster, the beam moves faster, too. In other words, when using the wedge 40, the sweep plates are impressed with a sawtooth sweep voltage in exact synchronization with the engine-driven two phase generator 22 and its circular sweep at the tube 30.

Across the other plates 60 and 61 of the tube 55 are impressed the signal from the engine itself, which may be of the type shown in Patent 2,518,427 or may be of another type. The signal may be from an engine magneto (for studying ignition) or may be from a vibration pickup (as shown in FIG. 1), or any other engine-generated signal may be used.

(f) *Operation of the FIG. 1 Apparatus*

When the engine 20 is running, the two-phase generator 22 generates a circular sweep 36 at the tube 30, necessarily perfectly synchronized with the engine cycle. The light caused by the circular beam 36 impinging on the fluorescent screen 37 passes through the optical wedge 40 and is focused by the lens 48 on the photo-transducer circuit. This voltage, properly amplified, if necessary, is impressed across the sweep plates 56 and 57 of the analyzer cathode ray tube 55 resulting in a sweep circuit there. Meanwhile, the signal plates 60, 61 are impressed with a signal from the portion of the engine being analyzed, as provided in my Patent No. 2,518,427 or in other engine analyzer circuits, giving a resultant pattern on the scope 55. The operation of the FIG. 21 device is identical, except for the omission of the lens 48.

(2) *DIFFERENT TYPES OF WEDGES AND THEIR CORRESPONDING TYPES OF SWEEPS (FIGS. 2 TO 13)*

As implied earlier, different types of optical wedges

can be used to obtain different types of sweep circuits. To illustrate this principle, several different types of wedges have been illustrated, together with some of their effects on the sweep and on the analyzer patterns.

5 (a) *Full 360° Uniformly Graduated Wedge 40 (FIGS. 2, 8, and 11)*

The wedge 40, as stated earlier, has its pattern 42 change uniformly with angle over a full circle from zero (or low, e.g., 10%) transmission to full (or high, e.g. 90%) transmission. This gives a saw-tooth wave of the linear type, as shown in FIG. 7 by the curve 46.

The wedge 40 may be turned around, in order to move the sweep from right to left instead of left to right, since the light will then start bright and gradually decrease at a uniform rate.

The 360° extent of the wedge 40 corresponds to the full 720° of rotation of the engine crankshaft cycle, each 2° thereof corresponding to 1° of light wedge. Thus, in 20 an ignition diagram 65, such as that shown in FIG. 8, patterns for every cylinder appear. The same thing happens in the radio-frequency pattern 66 shown in FIG. 11, where there are gaps 67 between each cylinder's diagram 68.

25 (b) *Short-Arc Uniformly Graduated Wedge 70 (FIGS. 3 and 9)*

The wedge 70 shown in FIG. 3 is adapted to enlarge 30 a portion only of the complete engine cycle and to exclude the rest of the cycle. This makes it possible to enlarge the diagram for each cylinder one cylinder at a time and study it more thoroughly. Thus, in an 18-cylinder engine, a segment 71 extending 20° of arc will cover 35 one-eighteenth of the complete engine cycle and, by having the wedge 70 rotatable, can be used to show the complete pattern of one cylinder and to take up the whole screen 63 with this one cylinder (see FIG. 9).

The segment 71 is graduated uniformly with angle, 40 from zero transmission at 0° to full transmission at 20°. The large 340° segment that remains is blank and gives full transmission. The resultant curve 73 on the FIG. 7 diagram shows a steep linear slope extending for 20° and then perfectly flat for the remaining 340°.

A typical ignition pattern 74 obtained from one cylinder by using the wedge 70 is shown in FIG. 9, where it will be seen to be a greatly enlarged (spread-out) version of one-eighteenth of the FIG. 8 pattern.

(c) *Two-Level Wedge 75 for Square Waves (FIG. 4)*

50 When a square wave sweep is desired, a wedge 75 like that shown in FIG. 4 may be used. One segment 76 (shown here as 15°) is completely opaque and another segment 77 (shown here as 345°) is fully transparent. 55 Alternately the two segments 76 and 77 may be any two levels of transmission; just so that each is constant in itself. Also, the proportions shown are exemplary only, and can be varied to suit conditions. This results in the voltage curve 78 shown in FIG. 7.

60 (d) *Gap-Eliminating Wedge 80 (FIGS. 5 and 12)*

The wedge 80 shown in FIG. 5 is of a novel type, designed for use with radio-frequency analyzer ignition circuits to solve the problem indicated in FIG. 11, where 65 there are gaps 67 in the pattern between each cylinder. If there normally were no gaps like this, then the presence of a gap for a whole cylinder would more clearly indicate trouble that should be given immediate attention.

So the wedge 80 provides two types of segments 81 and 70 82 that alternate. Each segment 81 is uniformly of one transmission, which is different from that of every other segment 81. Thus, in an eighteen-cylinder engine, there are eighteen segments 81, whose length corresponds to the gaps 67 in the curve of FIG. 11. The eighteen segments 75 81 are of eighteen different transmissions—stepped

at the rate of 100% transmission ± 18 , or 5.55%, and each one is uniform over its arc, which (for purposes of illustration) we shall assume to be 8° .

On the other hand, the eighteen segments 82 correspond to actual firing time (elements 68 in the pattern 66) which we shall assume to occupy 12° (referring here, as in the 8° segments, to arc of the light wedge). All have their density vary uniformly from the level of the segment 81 on one side to the level of the segment 81 on the other side.

As a result, during each cycle, the voltage level will vary uniformly during the scanning of each segment 82 and will be unchanged during the scanning of each segment 81. The curve 83, shown in FIG. 7, results, with sloped portions 84, corresponding to the segments 82 where the voltage increases, and level portions 85, corresponding to the segments 81. This means that the sweep at the cathode ray tube 55 will move in jerks, eliminating the level portions 81 to zero length. Because of this, the signal that produces the R.-F. diagram 66 of FIG. 11 when using the wedge 40 will produce the R.-F. diagram 86 in FIG. 12 when the wedge 80 is used. The gaps 67 that show on the diagram 66 between the energized portions 68, are eliminated, and the curve will appear as continuous, under normal conditions. Trouble is therefore easily spotted, as is shown in FIG. 12, when the missing portion 87 means that one cylinder gave no R.-F. signal, being shorted out. This shows much clearer and is more easily detected than the missing portion 69 in the diagram 66.

(e) *Half-and-Half Slow-Fast Wedge 90 (FIGS. 6 and 10)*

A wedge 90 shown in FIG. 6 makes it possible to scan the complete engine while also picturing one cylinder of the engine in expanded form, i.e. fast sweep. This wedge 90 will give a sweep that results in a spread-out diagram of that cylinder without omitting the diagram for any cylinder. By using a cylinder-cycle selector switch, the engineer can continue to watch the complete engine cycle while examining each individual cylinder in detail, one at a time, going from cylinder to cylinder.

In the wedge 90, a segment 91 (which in an 18 cylinder engine will extend 20° on the light wedge) is graduated uniformly between zero transmission and 50% transmission. The remaining segment 92 (which in this example will occupy 340°) varies uniformly from 50% transmission to 100% transmission. (The variations in transmission could vary, as a 20° arc from 12% to 52% transmission and a 340° arc from 52% to 92% transmission.) As a result, the curve 93 shown in FIG. 7 is obtained, having a steeply sloped portion 94 extending the first 20° and a more flatly sloped portion 95 extending the remaining 340° .

In order to illustrate one type of diagram that may result from the wedge 90, FIG. 10 is included. Here a diagram 96 clearly shows one cylinder occupying one-half 97 of the screen 63, while the remaining 17 cylinders occupy the remaining half 98 of the screen 63.

It should be noted that the diagrams shown in FIGS. 8, 9, and 10 are all obtained from the same basic engine signal. Thus, the FIG. 8 diagram 65 shows all 18 cylinders, and each one occupies the same length; the FIG. 9 diagram 74 shows one cylinder only, and in the FIG. 10 diagram 96, half the picture is occupied by one cylinder and the remaining half by the other 17 cylinders. Note that FIGS. 8 and 10 show one of the engine spark plugs with an open secondary circuit at 99. If further investigation of this particular cylinder is desired, it can be obtained by shifting the initiation of the sweep in FIG. 10, to bring the signal for that cylinder into the position where it occupies the left half of the diagram. Or the wedge used for the FIG. 9 pattern may be used.

(f) *Composite Four-Band Optical Wedge 100 (FIG. 13)*

It is possible to obtain the results of several or indeed all of the wedges shown on a single disc by providing

a plurality of annular bands, each band being graduated in a different way. This principle is illustrated by a wedge 100 shown in FIG. 13. Here four bands 101, 102, 103, and 104 are shown, though there could as well be two, three, five, or any other number of bands.

The outer annular band 101 is graduated exactly like the wedge 40 in FIG. 2, that is, uniformly from zero transmission to 100% transmission over the full 360° circle. The next inner band 102 is graduated exactly like the wedge 70 shown in FIG. 3, that is, from zero transmission to full transmission in a 20° arc 105 with the remaining 340° arc 106 at full transmission. The next inner band 103 is graduated like the wedge 75 shown in FIG. 4, that is, a 15° segment 107 at zero transmission and a 345° segment 108 at 100% transmission. The innermost band 104 is graduated like the wedge 90 in FIG. 6, that is, from zero transmission to 50% transmission in a 20° segment 109 and uniformly from 50% to 100% transmission in the remaining 340° segment 110.

The composite wedge 100 is used by providing a voltage regulator and a selector switch that will act to vary in some manner the voltage impressed across the deflector plates of the circle-sweep-cathode-ray tube. One such arrangement is shown in FIG. 16 (to be explained later on in more detail) where an amplified engine-generated current is sent through a selector switch 112 comprising variable step-resistor having four positions each one of which determines a given radius of the circular sweep 136 and thereby sends the light formed on the screen 137 to any one of four predetermined radii corresponding to the four bands of the wedge 100. The circuit arrangement will be explained in more detail later on. Other means for varying the voltage could be used, and this example illustrates how a single disc may incorporate several different sweep circuit arrangements.

(g) *Multi-Wedge Disc 300 (FIGS. 24, 25, and 26)*

An alternative way of changing light wedges is illustrated in FIGS. 24, 25, and 26 where a multi-wedge disc 300 is shown. A plurality of wedges, each occupying a full disc and identical in size, are mounted at a uniform radius from the center of the single large disc 300, which is itself rotatable to place one at a time only of the wedges in its proper position between the cathode-ray tube and the light-sensitive transducer 50. The wedges are synchronized with each other to give the same zero point, by proper relative location on the disc 300. By way of example, four types of wedges 301, 302, 303, and 304 are shown mounted in the disc 300, but there may be more or fewer wedges. No shielding problem is created by this construction, since known types of baffles can be in contact with the disc 300. This disc 300 has the advantage that there is no need to prepare a special disc 100, nor is there any need for varying or even controlling the diameter of the circular sweep, thereby saving circuit elements, because each wedge is made uniform in density along each radial line. Each disc 301, 302, 303, and 304 may be rotatable, as by sun and planetary gears 325, and 326, for the purpose described in the next section.

Other features of the invention shown in FIGS. 24 and 25 and not related to this multi-wedge feature, are discussed later on.

(h) *Rotating the Wedge to Select the Cycle Initiation Point*

By making any wedge rotatable, the cycle may be initiated at any desired point. Thus the wedge 70 may be used to study any cylinder ignition diagram simply by rotating the wedge 70 until the proper cylinder ignition diagram is in a position occupying the 20° of arc. Moreover, the initiation of the sweep for that cylinder can be selected to initiate at any point of the cylinder cycle. Similarly, by rotation of the light wedge 40 relative to a supporting rotatable knurled ring 111 (see FIG. 16), the initiation of the cycle for the complete engine may be

made to fall at any desired point and may be used to time the analyzer to the engine cycle. This provides a very simple manner of adjusting the synchronization between the sweep and any engine-initiated signal to secure any desired point of initiation of the oscilloscope on the scope 55 or 155. Moreover, cycle initiation is controlled inside the aircraft cabin rather than having to adjust the synchronization at the engine itself.

One way of providing a rotatable wedge is shown in FIG. 16, where a four-band wedge 100 is held by a friction strip 181 in a cycle-indicating ring 182, which is rotatably mounted in a fixed cylinder index ring 183. A flange 184 on the ring 182 may comprise the forward portion of the light shield 154, so that the calibrations are outside the shield. The shield 184 and ring 182 are rotatable relative to the fixed cylinder index ring 183, and the wedge 100 is rotatable with or separately from the ring 182. A lever 185 is operable from outside the shield 154 to engage the wedge 100 and lock it against rotation relative to the ring 182. This lever 185 may be mounted on a fixed rear portion 154b of the shield 154, and may be disengaged when adjusting the wedge 100 so that the wedge 100 will rotate with the ring 182; then the lever 185 may be engaged to lock the wedge 100, while the ring 182 is rotated to get the proper adjustment between the ring 182 and the wedge 100.

In order to take full advantage of this cycle initiation device, one known cylinder should be differentiated, as by disconnecting its ignition leads to give an open circuit diagram. Or the engine can be wired to give an indexing pulse at a known point in the engine cycle. At any rate, once that cylinder or cycle position is identified, all cylinders and engine events are identified by the known firing order and other constants of the engine cycle of the engine.

Starting with a known cylinder, the light wedge 100 may be rotated, by disengaging the brake lever 185 and rotating the ring 182-flange 184 combination, until the ignition diagram of the identified cylinder is correctly located relative to the index of the indicator tube 155. If it is the No. 1 cylinder, then the ignition diagram for the No. 1 cylinder is located at the beginning of the horizontal sweep trace on the indicator cathode-ray tube 155, at zero on the index. Then the light wedge 100 is locked at this point by the lever 185.

Next, the ring 182 is rotated until the arrow labeled "IGN" points at the numeral "1" on the ring 183. The analyzer is now timed to the engine, and all the timing has been done in the cabin at the analyzer, instead of having to rotate the engine generator, as was necessary in the past. The brake lever 185 is now disengaged.

Once this initial synchronization is done, the sweep of the indicator tube can be initiated at any selected point in the cylinder cycle (as shown on the ring 182) for any selected cylinder (as shown on ring 183) by placing the selected cycle point on the ring 182 opposite the numeral indicating the selected cylinder on the ring 183. For example, if the "IGN" pointer is turned so that it points to the numeral "2" on the ring 183, the horizontal trace on the tube 155 will start at the beginning of the ignition cycle of the No. 2 cylinder. Any selected condition may similarly be displayed on the oscilloscope 155.

The discs 301, 302, 303, and 304 in the multi-wedge disc 300 may be rotated similarly, as shown in FIG. 26.

(i) *Alternative Selection of Cycle Initiation Point by Rotation of the Tube Using the Structure of FIG. 24*

Instead of rotating the light wedge relative to the circle-sweep cathode-ray tube, the tube may be rotated. With the apparatus of FIG. 16, rotation of the light wedge 100 is more convenient, but with the apparatus of FIG. 24, rotation of the cathode-ray tube 305 is more convenient. The deflection plates and other tube circuit connections are connected to their lead wires by means of appropriate independent slip rings 306, so that rotation of the tube

305 becomes possible. This is indicated diagrammatically, and satisfactory operation can be obtained by other means, as by flexible leads. When the tube 305 is rotatably mounted, the cycle switch 307 may be mounted concentrically with the main oscilloscope 308 and may have a toothed edge 310 that drives a gear 311. The gear 311 may be mounted on a shaft 312, and gear 313 also supported by the shaft 312 may drive a gear 314 mounted on the tube 305. The basic operation is still the same as that described in the preceding section.

(j) *Alternative Selection of Cycle Initiation Point Using A Magnetic Deflection Circuit (FIG. 25)*

As is well known, the electron beam in a cathode-ray tube may be deflected either electrically or magnetically. A circuit in which a circle-sweep cathode-ray beam is controlled by magnetic deflection is shown in FIG. 25. The cycle switch 307 and associated parts are like those of the FIG. 24 device, but the gear 313 drives a gear 315 which rotates a magnetic deflection yoke 316, while the cathode-ray tube 317 stays stationary. Slip rings 318 on the yoke 316 connect with leads 320, 321, and 322 leading to a three-phase generator 323. Again operation is like that described in section h above.

(k) *Indexing the Sweep Curve (FIGS. 14 and 15)*

The invention also makes it possible to provide indexing means in connection with any of the wedges so as to calibrate the pattern at the scope 55. This can be done by providing the wedge itself with radial lines of substantially different density from their portion of the wedge, e.g., of full transmission or of zero transmission at spaced intervals. For example, FIG. 14 shows a wedge 140 like the wedge 40 but with four openings or blank areas 141 spaced around it at regular (90°) intervals. When the light beam 36 strikes one of these areas 141, it transmits its full intensity to the photo-transducer 50, correspondingly affecting the sweep, as shown in curve 143 with its peaks 144 in FIG. 22, and showing as gaps 145 in FIG. 23. These lines 144 produce either full voltage or zero voltage at a particular location on the picture tube 55, corresponding to the degrees of arc where the lines are formed in the wedge, and therefore to corresponding degree in the engine cycle. Where the wedge is primarily like that of FIG. 2, the degree-indicating lines are preferably completely blank, as shown in FIG. 14, giving full transmission and thereby full voltage.

For use with curves like those of FIGS. 3 and 4, it may be more useful to have dark lines. These dark lines may be provided on the wedge itself, or they may be provided on a separate indexing disc 146 (FIG. 15) which carries nothing but a series of dark lines 147 and is adapted first to be synchronized with its wedge and then to be moved together with it when selecting the initiation points.

55 (3) *A MORE COMPLEX ANALYZER CIRCUIT (FIG. 16)*

To give some further indication of the versatility of this invention, I shall now describe a more complex circuit that takes advantage of some of the special features 60 flowing from generation of the sweep circuit of the engine analyzer tube by means optically-responsive to a circular sweep on an auxiliary cathode-ray tube. Several features of this circuit are substantially identical with that of a simple circuit, while other features have been shown in 65 modified form to illustrate alternate methods of accomplishing the same end results. In other instances the refinements described are completely absent from the simple circuit shown in FIG. 1.

The circuit and apparatus shown in FIG. 16 are adapted 70 for use with multi-engine aircraft and are therefore shown in connection with four engines 120 herein called engines A, B, C, and D respectively. In each instance, the engine A, B, C, or D rotates a magnet 121 of a three-phase generator 122a, 122b, 122c, and 122d at engine cycle speed: i.e., at one-half the crankshaft speed in a

four-cycle engine. (Obviously the invention is just as applicable to a two-cycle engine.) From poles 123, 124, and 125 of the generator 122 current is transmitted to a resolver 165a, 165b, 165c, or 165d, which provides two sine waves 90° out of phase and adjustable relative to the engine generator 121, to time the engine to the generator. The resolver is, in effect a continuous resistor with four brushes 166, 167, 168, and 169 mounted 90° apart and linked together mechanically as a unit. All four resolvers may be on a common resistor, or they may be separate resistors. Electrical insulation is provided so that the brushes 166 and 167, which are diametrically opposite each other, supply the current pickup which eventually will be impressed on the horizontal plates 131 and 132 of the cathode-ray tube 130, while the brushes 168 and 169, also diametrically opposite each other, pick up the current which will ultimately be used on the vertical deflection plates 133 and 134.

An engine selector switch 170 is provided into which are connected each of the four leads 171a, 172a, 173a, and 174a; 171b, and 172b, 173b, and 174b; 171c, 172c, 173c, and 174c; 171d, 172d, 173d, and 174d, from each of the four resolvers 165a, 165b, 165c, and 165d, one for each of the engines A, B, C, and D. The selector switch 170 provides a means for placing the four leads of any one engine into contact with corresponding output leads 175, 176, 177, and 178, the leads from other three engines going at that time to a dead end or broken circuit. The four leads 175, 176, 177, and 178 pass through suitable amplifying and automatic voltage-regulating means 179 to a sweep selector switch 112 which has somewhat been described above. It comprises four step resistor elements 113, 114, 115, and 116 (one for each of the four leads 175, 176, 177, and 178) all linked together for step movement so that all the resistor elements 113, 114, 115, and 116 of the switch are either at step 1, or step 2, or step 3, or step 4. This changes the voltage levels in the lead lines 175, 176, 177, and 178 and therefore changes the voltage impressed upon the deflection plates 131, 132, 133, and 134 of the cathode-ray tube 130, which in turn change the amount of deflection of the cathode-ray 135 to produce any of four desired radii.

FIG. 27 illustrates in diagrammatic form a modification of a portion of the FIG. 16 circuit, showing the fact that an engine selector switch 250 may be interposed between the engine generators 122a, 122b, 122c, and 122d and a cycle switch 260, instead of using the FIG. 26 arrangement.

Except for the refinements heretofore described, the cathode-ray tube 130 operates substantially the same as the tube 30, giving a circular sweep 136 on its fluorescent screen 137, the difference being that the circular sweep 136 may be adjusted to any one of four radii.

The light produced on the fluorescent screen 137 by the cathode ray 135 is transmitted through the optical wedge 100 and focused by a lens 148 on a photo-transducer 150. (The lens 148 may, of course, be omitted by selecting the proper photo-transducer.) The only difference in this part of the device is that the wedge 100 is of the four-band type heretofore described, so that the sweep selector switch 112 makes it possible to send the light beam through any one of the fourbands 101, 102, 103, or 104 of the wedge 100.

The photo-transducer element 150 shown is of the type having a voltage impressed across it from a source 151 and in which the resistance to that voltage is varied by the light falling on the element 150. It may be a photo-multiplier, such as the R.C.A. tube 931-A. As a result, the light beam 136 produces a relatively large electric signal which may or may not need amplification by an amplifier 152 before it is impressed as the sweep across the "horizontal deflection" plates 156 and 157 of a cathode ray oscilloscope 155. A light shield 154 is again provided around the assembly made up of the tube 130, wedge 100, lens 148, and transducer 150.

The initiation of the cycle for each engine A, B, C, and

D may be controlled by its resolver 165a, 165b, 165c, and 165d which may be synchronized to the engine once and for all, and left there, or may be made adjustable at any time, by rotating the four brushes in tandem. Once each engine has had its cycle synchronized to that of the other engines by adjustment of the resolvers 165, cycle initiation for all engines may be changed by rotating the optical wedge 100, as described earlier.

Many types of engine signals may be analyzed, and for purposes of illustration, a typical condition switch 180 is shown diagrammatically with 36 conditions possible, including eight for each engine (or 32 altogether), three for coupling engine A to each of the other three engines, for synchronization check, and one special switch. Typical uses of the analyzer are illustrated by the labels on the lines leading from engine D (using circuit connection as described in my Patent 2,518,427), showing that there is a magneto pickup for ignition analysis, a temperature pickup, a pressure pickup, a vibration pickup, a motion pickup, a torque pickup, a propeller dynamic balance pickup, and a velocity pickup. Any one of these pickups may be selected at the condition switch 180 for any of the engines A, B, C, and D, and studied, by whichever of the four sweeps is most appropriate.

25. 4. OTHER MEANS FOR OBTAINING A CIRCULAR SWEEP (FIGS. 17-20)

It should be understood that there are many ways of obtaining a circular sweep and the invention is not to be confined to any one of them. Examples already given have been the use of a two-phase generator and of a three-phase generator with a resolver.

(a) *Obtaining a Circular Sweep Directly From a Three-Phase Generator. (FIG. 17)*

FIG. 17 shows how a three-phase generator 200 may be connected to three pairs of deflector plates 201, 201a, 202, 202a, 203, 203a, arranged 120° apart in a cathode-ray tube 204, to produce a circular sweep. One of each pair of plates, 201, 202, and 203 are connected to the three phase generator 200, while the other plate 201a, 202a, and 203a of each pair may be connected to a common lead. Since the three plates are 120° apart and since the phase variation is exactly as generated, the electron beam will move in a circular path.

(b) *Obtaining the Circular Sweep Indirectly From a Three-Phase Generator. (FIG. 18)*

FIG. 18 shows another way of obtaining a circular sweep from the three-phase generator 200, again using the tube 204 with three pairs deflector plates 201, 201a, 202, 202a, and 203, 203a. Here, a resolver 205 is interposed, with its three brushes 206, 207, and 208 mounted for movement as a unit, 120° apart. This makes it possible to initiate the sweep cycle at any point of the engine cycle.

(c) *Obtaining a Circular Sweep Directly From a Single-Phase Generator. (FIG. 19)*

FIG. 19 shows how to obtain a circular sweep directly from a single phase generator 210. By utilizing parallel resistance 211 and capacitance 212 from the generator 210, and impressing them across the respective pairs of deflector plates 213, 214 and 215, 216 of a cathode-ray tube 217, at a desired frequency, the impedances may be balanced to give two sine waves 90° out of phase which, when impressed across the cathode-ray tube's vertical and horizontal plates, as shown, result in a circular sweep 218. The disadvantage of this particular arrangement is that it is frequency-responsive, and will change from a circle to an ellipse at other frequencies than the design frequency. For some uses, where a single light wedge of adequate radius relative to a limited speed range is used, this makes no difference whatever, since the optical wedge if uniform in light transmission along any given radius, will

compensate for it, but for other uses, it is not as suitable as some of the forms shown heretofore.

(d) *Obtaining a Circular Sweep From a Three-Phase Generator Using Impedance Lag. (FIG. 20)*

The same principle used with the single-phase generator 210 can be used with the more common three-phase generators, as shown in FIG. 20. Here a generator 220 supplies current to a resolver 221 with only two brushes 222, 223 which are rotatable together 180° apart. From then on, the circuit is like that shown in FIG. 19, and the same numbers are used. This circuit makes it possible to use a single amplifier, when amplification is required, to amplify the signal before applying it to the circle-sweep cathode-ray tube.

(e) *Obtaining a Circular Sweep From a Three-Phase Generator Using Magnetic Deflection Coils (FIG. 25)*

While the use of electrical deflection plates has been shown, magnetic deflection can also be used, and FIG. 25 illustrates how a three-phase generator 323 can be connected directly to a magnetic deflection yoke 316. The yoke 316 includes six coils spaced at 60° intervals, three diametrically opposite pairs, each pair being across two of the three lines 320, 321, and 322 coming from the generator 323. It suffices to say here that the deflection again results in a circular pattern.

To those skilled in the art to which this invention relates, many changes in construction and widely differing embodiments and applications of the invention will suggest themselves without departing from the spirit and scope of the invention. The disclosures and the description herein are purely illustrative and are not intended to be in any sense limiting.

I claim:

1. In an engine analyzer, a first cathode-ray tube, engine-operated means to generate in said tube a circular cathode-ray sweep in cycle with the engine that generates it; means for transforming the electron beam in said circular sweep into a light beam moving in a circle; means to change the intensity of the light during each cycle according to the angular position of the light beam in its circular path; means, responsive to said change in light intensity, to correspondingly vary an electrical signal; and means to impress said electrical signal upon the sweep plates of an engine analyzer cathode-ray tube.

2. The analyzer of claim 1 in which the engine that generates the circular sweep is used as the source of a signal impressed on the other plates of the engine analyzer tube.

3. In an engine analyzer, a first cathode-ray tube, means driven by the engine being analyzed to generate in said tube a circular cathode-ray sweep in cycle with said engine; means for transforming said circular sweep into a light beam moving in a circle; means to change the intensity of the light according to its angular position during each cycle; means, responsive to said change in light intensity, to correspondingly vary an electrical signal; means to impress said electrical signal upon the sweep plates of an engine analyzer cathode-ray tube to provide a rectilinear sweep in synchronism with the engine; and means to place a signal to be analyzed across the other plates of said engine analyzer tube.

4. An automatically synchronized cathode-ray sweep apparatus for an engine analyzer where one set of plates of a primary cathode-ray tube is utilized for the sweep circuit and the other set of plates is made responsive to an engine initiated signal whereby the engine performance may be studied, comprising: a generator operated by the engine being studied and therefore in synchronization with said engine, means for obtaining from said generator a plurality of substantially equal signals out of phase; an auxiliary cathode-ray tube having a corresponding plurality of pairs of deflection plates connected to said generator signals so as to generate a circular path for an electron beam in said tube; an instantaneously fluo-

rescent screen converting said beam into light; an optical wedge through which the light from said tube passes; a photo-transducer receiving the light that passes through said wedge and actuated thereby to vary an electric signal; and means to impress said electric signal across said primary cathode-ray tube sweep circuit plates.

5. The apparatus of claim 4 wherein said light wedge has its transmission change uniformly with change in angle thereof over its full 360° extent.

10 6. The apparatus of claim 4 wherein the light transmission of said light wedge changes uniformly with changes in angle over a portion of a circle and remains uniform over the remainder of said circle.

7. The apparatus of claim 4 wherein the light transmission of said light wedge varies uniformly with changes in angle over one portion of a circle and varies uniformly with changes in angle at a different rate, over another portion of said circle.

8. The apparatus of claim 4 wherein the light transmission of said light wedge remains constant at one level over one portion of a circle and remains constant at a different level over another portion of a circle.

9. The apparatus of claim 4 wherein said light wedge consists of a circular wedge with two types of segments that alternate, each of one type of segment having uniform light transmission but at a different level from that of a preceding segment of its type, each of the other type of segment changing its transmission at a uniform rate between the levels of its two adjacent segments of the other type.

30 10. The apparatus of claim 4 wherein said generator is a three-phase generator and wherein there are three pairs of parallel plates in axial succession in said auxiliary cathode-ray tube, the pairs lying 120° apart, one plate of each pair being connected to one of the three poles in said generator.

11. The apparatus of claim 4 wherein said generator is a three-phase generator and wherein there are three pairs of magnetic coils spaced around said auxiliary 40 cathode-ray tube, the two coils in each pair lying 180° apart and the pairs 60° apart and connected to the three poles in said generator.

12. The apparatus of claim 4 wherein there are two pairs of parallel deflection plates in said auxiliary cathode-ray tube, and means for obtaining from said generator two signals 90° out of phase.

45 13. The apparatus of claim 12 wherein the generator is coupled to the auxiliary cathode-ray tube by a resistance coupling to one set of deflection plates and a capacitance coupling to the other set.

50 14. The apparatus of claim 4 wherein a plurality of said wedges are mounted at the same radius in a rotatable disc, so that the wedges can be changed by rotating said disc.

15. The apparatus of claim 4 wherein a lens is employed to focus the light beam on said photo-transducer.

16. An automatically synchronized cathode-ray sweep apparatus for an engine analyzer where one set of plates of a primary cathode-ray tube is utilized for the sweep circuit and the other set of plates is made responsive to an engine initiated signal whereby the engine performance may be studied, comprising: a generator operated by the engine being studied and therefore in synchronization with said engine, means for obtaining from said generator two substantially equal signals 90° out of phase; an auxiliary cathode-ray tube having two pairs of parallel deflection plates connected to said generator signals so as to generate a circular path for an electron beam in said tube; cycle selection means between said

60 70 generator and said cathode-ray tube, comprising two pairs of brushes 90° apart, the brushes in each pair being diametrically opposite each other, said two pairs being linked in tandem for rotation relative to a continuous resistor; an instantaneously fluorescent screen converting 75 said beam into light; an optical wedge through which

the light from said tube passes; a photo-transducer receiving the light that passes through said wedge and actuated thereby to vary an electric signal; and means to impress said electric signal across said primary cathode-ray tube sweep circuit plates.

17. An automatically synchronized cathode-ray sweep apparatus for an engine analyzer where one set of plates of a primary cathode-ray tube is utilized for the sweep circuit and the other set of plates is made responsive to an engine initiated signal whereby the engine performance may be studied, comprising: a generator operated by the engine being studied and therefore in synchronization with said engine, means for obtaining from said generator a plurality of substantially equal signals out of phase; an auxiliary cathode-ray tube having a corresponding plurality of pairs of deflection plates connected to said generator signals so as to generate a circular path for an electron beam in said tube; an instantaneously fluorescent screen converting said beam into light; an optical wedge through which the light from said tube passes, said wedge having a plurality of annular concentric bands, each with different light-transmission characteristics; means for varying the radius of the circular path of the electron beam in said auxiliary cathode-ray tube, for selectively causing the light beam to pass through different bands of said wedge; a photo-transducer receiving the light that passes through said wedge and actuated thereby to vary an electric signal; and means to impress said electric signal across said primary cathode-ray tube sweep circuit plates.

18. An automatically synchronized cathode-ray sweep

apparatus for an engine analyzer where one set of plates of a primary cathode-ray tube is utilized for the sweep circuit and the other set of plates is made responsive to an engine initiated signal whereby the engine performance

5 may be studied, comprising: a generator operated by the engine being studied and therefore in synchronization with said engine, means for obtaining from said generator a plurality of substantially equal signals out of phase; an auxiliary cathode-ray tube having a corresponding 10 plurality of pairs of deflection plates connected to said generator signals so as to generate a circular path for an electron beam in said tube; an instantaneously fluorescent screen converting said beam into light; an optical wedge through which the light from said tube passes; means for 15 rotating said wedge for changing the initiation point of the cycle; a photo-transducer receiving the light that passes through said wedge and actuated thereby to vary an electric signal; and means to impress said electric signal across said primary cathode-ray tube sweep circuit plates.
